UNITED STATES PATENT OFFICE

134,614

DESIGN FOR A FABRIC

Bernadine Oeffner, Chandler, Minn.

Application June 3, 1942, Serial No. 107,085

Term of patent 3½ years

To all whom it may concern:

Be it known that I, Bernadine Oeffner, a citizen of the United States, residing at Chandler, in the county of Murray and State of Minnesota, have invented a new, original, and ornamental Design for a Fabric, of which the following is a specification, reference being had to the accompanying drawing, forming part thereof, and wherein is illustrated a view of a piece of fabric showing a unit of my new design, which unit is repeated in regular succession as indicated by the extension beyond the unit boundaries.

I claim:

The ornamental design for a fabric, as shown and described.

BERNADINE OEFFNER.
